ODORIZED GAS AND METHOD FOR ODORIZING THE SAME

John L. Eaton, Whitemarsh, Pa., and George E. Hinds, Houston, Tex., assignors, by mesne assignments, to Pennsalt Chemicals Corporation, a corporation of Pennsylvania

No Drawing. Application December 23, 1953
Serial No. 400,098

18 Claims. (Cl. 48—195)

This invention relates to alkyl thioethers containing at least one tertiary alkyl group, and relates also to the use of these compounds as gas odorants.

Natural gas, the propane and butane fractions of liquified petroleum gases, and some types of manufactured gases possess practically no inherent odor, and odorization of these gases, so that they will be detectable at low concentrations in the atmosphere, has been practiced for many years. In the gas industry, it is standard practice to add a controlled amount of a strongly odoriferous material to act as a warning agent in the case of a gas leak, and many states have laws requiring that gas be odorized to a specified minimum level as a safety measure. Adequate odorization is not only a safety measure but results also in substantial economies since pipe line leaks, which may amount in the aggregate to considerable gas loss, may be promptly detected and repaired. Also, these leaks would not be detected if the gas were not odorized.

Gas odorants in current use belong to the general category either of mercaptans or organic sulfides. Odorants in either category may be pure compounds or mixtures, and may be used in concentrated form or diluted with relatively inodorous materials. Mercaptans have a higher odor intensity but are easily oxidized by traces of oxygen in a pipe line to relatively inodorous disulfides. Organic sulfides are of lower odor intensity than mercaptans, but are stable to pipe line oxidative conditions so that, if added to the gas in sufficient amount, the odor will be transmitted unimpaired over long distances.

An odorant of acceptable quality should be harmless and neither toxic nor nauseating, non-corrosive, chemically inactive, insoluble in water, inexpensive and readily available, burn completely without harmful or odorous products of combustion, be stable and not adsorbed by mains or meters, and should possess a penetrating odor similar to the artificial gas smell.

In accordance with the present invention, alkyl thioethers containing a tertiary alkyl group are used as sulfide-type odorants, possessing the oxidation stability common to thioethers and possessing a higher odor intensity than other alkyl thioethers.

Among the compounds which are useful as odorants in accordance with the invention may be mentioned tertiary butyl, methyl, ethyl, propyl, and isopropyl sulfides, and tertiary amyl, methyl, ethyl, propyl, and isopropyl sulfides. Other compounds of this type may also be employed, the alkyl chain length being limited only by the vapor pressure of the compounds, i. e., the compounds must have a vapor pressure sufficiently high that the compound may be vaporized into the gas stream in a pipe line in amount sufficient for adequate odorization. It is also essential that a tertiary carbon atom be directly linked to the sulfur atom.

In practice, odorization is usually effected by means of an injection type odorizer in which the odorant is pumped into the gas stream and vaporized, or a metered portion of gas is passed over a wick and saturated with the odor-

ant. These are conventional expedients in the art, and any other type of odorizing equipment may also be employed. The odorant is generally added to the gas in a pipe line at the rate of about 0.2 pound to 3.0 pounds of odorant per million cubic feet of gas with the preferred rate being about 1.5 pounds of odorant per million cubic feet of gas.

The invention will be further illustrated by reference to the following specific examples:

10

EXAMPLE 1

Preparation of tertiary butyl ethyl sulfide

A two gallon autoclave was charged with 1261 grams (14 mols) of tertiary butyl mercaptan, 950 grams (14.72 mols) of ethyl chloride and 616 grams (15.4 mols) of sodium hydroxide dissolved in 2308 grams of water, this being the calculated amount of water to yield a saturated salt solution if the reaction goes to completion. The reagents were chilled before charging and the autoclave was rapidly closed after charging was completed. The autoclave was then heated, with continuous agitation, to a temperature of 150° C. in 45 minutes, maintained at a temperature of 150° C. for 15 minutes, rapidly cooled, and discharged, using conventional precautions to avoid loss of volatile components.

After distilling off unreacted ethyl chloride, the oil layer was steam distilled, dried azeotropically, and fractionally distilled. Ethyl chloride and mercaptan heads were removed and 1511 grams of product were obtained as a cut boiling at 119 to 119.5° C.

EXAMPLE 2

Preparation of tertiary butyl isopropyl sulfide

35 A two gallon autoclave was charged with 910 grams of tertiary butyl mercaptan, 800 grams of isopropyl chloride, and a solution of 450 grams of sodium hydroxide in 2850 grams of water. The autoclave was heated to a temperature of 126° C. in 40 minutes and was held at a temperature of 125 to 135° C. for 70 minutes, during which time the pressure varied between 80 and 100 p. s. i. g. The autoclave was cooled to a temperature of 25° C. and discharged. 1,580 grams of crude oil layer were recovered having a specific gravity of 0.840.

45 The Engler distillation of this layer was as follows:

	°C.		°C.
IBP	37.0	60	55
1	39.0	70	64
5	40	80	98
10	42	90	132
20	43.5	95	135
30	45	FBP	141
40	48	Recov.	97
55	50.5		

60 1,163 grams of neutral crude product were fractionally distilled. After removing unreacted isopropyl chloride and tertiary butyl mercaptan, 142.5 grams of tertiary butyl isopropyl sulfide were recovered, boiling at 132° C. and having a specific gravity of 0.815.

EXAMPLE 3

Preparation of tertiary amyl ethyl sulfide

65 A two gallon autoclave was charged with 1050 grams (10.1 mols) of tertiary amyl mercaptan, 450 grams (11.2 mols) of sodium hydroxide, and 660 grams (10.2 mols) of ethyl chloride in 2000 grams of water. The autoclave was then heated, while subjecting the mixture to agitation. The temperature was maintained at 130 to 140° C. for two hours, during which time the pressure varied from 80 to 100 p. s. i. g. The autoclave was

cooled to 24° C. (pressure 5 p. s. i. g.), vented, and discharged. 1,482 grams of oil layer, and 2,646 grams of saline solution were obtained. Titration of the water layer indicated that 77.5% of the total sodium hydroxide had been consumed. The crude oil layer had a specific gravity of 0.831 and the Engler distillation of this layer was as follows:

	° C.		° C.
IBP	35.0	60	136.0
1	38.0	70	143.5
5	45.0	80	148
10	65	90	151
20	108.5	95	159
30	120	FBP	163
40	124.5	Recov.	96
50	131.5		

1110.5 grams of crude product were fractionally distilled, and after distilling off the unreacted mercaptan and ethyl chloride, 465 grams of tertiary amyl ethyl sulfide were recovered as a clear colorless liquid boiling at 146 to 148.5° C. and having a specific gravity of 0.840.

EXAMPLE 4

A room test procedure was used to estimate odor thresholds of various materials. The test consisted of the vaporization of successive increments of a dilute ethanolic solution of the odorant to be evaluated into a nitrogen stream which was passed at a uniform rate into an electric fan which circulated the odor throughout a closed room, the exact time of each injection being recorded. This room had a volume of 1233 cubic feet. A panel of six observers was seated at random in the room prior to the start of the test, in clear view of a clock. At the end of the test, each observer independently recorded the earliest time at which odor had become apparent to him. The odorant concentration in the room at any given time was calculated from the known injection schedule of the odorant solution and thus the threshold concentration for each observer was determined.

As shown by the following table, tertiary butyl ethyl sulfide was rated as stronger than mixed lower alkyl ethyl sulfides by three of the five observers, with one observer considering the intensities equal and one considering the tertiary butyl ethyl sulfide as weaker. Four out of the six observers considered tertiary butyl methyl sulfide as equal to the corresponding ethyl sulfide, with one rating the methyl homologue stronger and one rating it weaker:

TABLE I

Odorant	Threshold value, lbs./10 ⁸ C. F.							
	Observer						Average	
	A	B	C	D	E	F	faint perception	definite perception
Me-tert-BuS	0.2	0.4	0.2	2.0	0.2	0.2	0.5	1.2
Et-tert-BuS	0.2	0.4	0.2	0.2	1.0	0.1	0.2	0.4
Mixed lower alkyl-ethyl sulfides	0.5	0.2	0.2	4.0	4.0	-----	1.2	1.6

¹ One observer fails to detect at indicated level.

² Two observers fail to detect at indicated level.

Comparisons between tert-BuSET, tert-AmSET, and mixed amylmethyl sulfides were made, using an apparatus which presents, to the nose of the observer, a definitely known concentration of odorant in gas-air mixture. The tests, as originally conducted, were duplicated two days later, but with the order of presentation of the odorants reversed, to cancel out any effect the order of presentation may have on the observations.

Odorant	Threshold, lbs./10 ⁸ C. F.			
	Observer A		Observer B	
	order as listed	order reversed	order as listed	order reversed
tert-BuSET	0.55	0.3	0.4	0.2
tert-AmSET	1.5	0.65	0.2	0.3
Mixed AmSMe	2.7	1.1	2.4	0.4

It will be obvious to those skilled in the art that many modifications may be made within the scope of the present invention without departing from the spirit thereof, and the invention includes all such modifications.

We claim:

1. A method of odorizing a gas which comprises mixing the gas to be odorized with a compound having the structure

in which R is selected from the group consisting of tert-butyl and tert-amyl radicals and R₁ is selected from the group consisting of methyl, ethyl, propyl, and isopropyl radicals.

2. A method of odorizing a gas which comprises mixing the gas to be odorized with a compound having the structure

3. A method of odorizing a gas which comprises mixing the gas to be odorized with a compound having the structure

in which R is a tert-amyl radical and R₁ is selected from the group consisting of methyl, ethyl, propyl and isopropyl radicals.

4. A method of odorizing a gas which comprises mixing the gas to be odorized with a compound having the structure

in which R is selected from the group consisting of tert-butyl and tert-amyl radicals.

5. A method of odorizing a gas which comprises mixing the gas to be odorized with a compound having the structure

in which R is selected from the group consisting of tert-butyl and tert-amyl radicals.

6. A method of odorizing a gas which comprises mixing the gas to be odorized with a compound having the structure

in which R is selected from the group consisting of tert-butyl and tert-amyl radicals.

7. A method of odorizing a gas which comprises mixing the gas to be odorized with a compound having the structure

in which R is selected from the group consisting of tert-butyl and tert-amyl radicals.

8. A method of odorizing a gas which comprises mixing the gas to be odorized with tert-butyl ethyl sulfide.

9. A method of odorizing a gas which comprises mixing the gas to be odorized with tert-butyl methyl sulfide.

10. A method of odorizing a gas which comprises mixing the gas to be odorized with tert-butyl isopropyl sulfide.

11. A method of odorizing a gas which comprises mixing the gas to be odorized with tert-butyl propyl sulfide.

12. A method of odorizing a gas which comprises mixing the gas to be odorized with tert-amyl ethyl sulfide.

13. A method of odorizing a gas which comprises mixing the gas to be odorized with an alkyl thioether having a tertiary carbon atom linked to the sulfur atom and having a vapor pressure sufficiently high that the compound may be vaporized into a gas stream in a pipe line in amount sufficient for adequate odorization.

14. A method of odorizing a gas which comprises mixing the said gas with an alkyl thioether having a tertiary carbon atom linked to the sulphur atom and having a vapor pressure sufficiently high that the compound may be vaporized into the said gas, the said thioether being present at a concentration of 0.2 to 3 pounds per million cubic feet of gas.

15. An odorized gas comprising a major proportion of a member of the class consisting of natural gas, manufactured gas and mixtures thereof, and a minor proportion of an alkyl thioether having a tertiary carbon atom linked to the sulphur atom, said thioether being present at a concentration of 0.2 to 3 pounds per million cubic feet of gas.

16. An odorized gas comprising a major proportion of a member of the class consisting of natural gas, manufactured gas, and mixtures thereof, and a minor proportion of an organic sulfide having the structure

in which R is selected from the group consisting of tert-butyl and tert-amyl radicals and R_1 is selected from the group consisting of methyl, ethyl, propyl, and isopropyl radicals, said organic sulfide being present at a concentration of 0.2 to 3 pounds per million cubic feet of gas.

17. An odorized gas comprising a major proportion

of a member of the class consisting of natural gas, manufactured gas and mixtures thereof, and a minor proportion of an organic sulfide having the structure

5 in which R is a tert-butyl radical and R_1 is selected from the group consisting of methyl, ethyl, propyl, and isopropyl radicals, said organic sulfide being present at a concentration of 0.2 to 3 pounds per million cubic feet of gas.

10 18. An odorized gas comprising a major proportion of a member of the class consisting of natural gas, manufactured gas and mixtures thereof, and a minor proportion of an organic sulfide having the structure

15 in which R is a tert-amyl radical and R_1 is selected from the group consisting of methyl, ethyl, propyl and isopropyl radicals, said organic sulfide being present in the gas mixture at a concentration of 0.2 to 3 pounds per million cubic feet of gas.
